(57) **CLAIM**

The ornamental design for a pull tab for a bottle, as shown and described.

DESCRIPTION

FIG. 1 is a front perspective view of a pull tab for a bottle showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a top plan view of the bottle after separation.

In the drawings, the broken lines show portions of a bottle that form no part of the claim.
